Primary Examiner — Calvin E Vansant*Assistant Examiner* — Benjamin L. Gray*(74) Attorney, Agent, or Firm* — Thomas A. O'Rourke;
James Bongiorno; O'ROURKE IP LAW PLLC(57) **CLAIM**

The ornamental design for a pill bottle cap remover as shown and described.

DESCRIPTION

FIG. 1 is a top view of a new design for a pill bottle cap remover; the bottom view is a mirror image of the top view shown;

FIG. 2 is a first end view thereof;

FIG. 3 is a second end view thereof; and,

FIG. 4 is a front view thereof; the rear view is a mirror image of the front view shown.

The broken lines shown in the drawings depict portions of the pill bottle cap remover that form no part of the claimed design.
